KITCHEN MIXER

Alwin Kost, Portland, Oreg.

Application July 31, 1950, Serial No. 11,499

Term of patent 14 years

(Cl. D44—1)

To all whom it may concern:

Be it known that I, Alwin Kost, a citizen of the United States of America, residing at Portland, in the county of Multnomah and State of Oregon, have invented a new, original, and ornamental Design for a Kitchen Mixer, of which the following is a specification, reference being had to the accompanying drawings, forming part thereof.

In the drawings—

Fig. 2 is a side elevation of the same.

Fig. 3 is a top plan view of the same.

I claim:

The ornamental design for a kitchen mixer, as shown.

ALWIN KOST.
